SPRAY GUN

Earl K. Hughes, 1436 Olivina Ave., Livermore, Calif.
Filed Oct. 15, 1965, Ser. No. 496,514
5 Claims. (Cl. 239—348)

The present invention relates to improvements in a spray gun and it consists in the combination, construction and arrangement of parts as hereinafter described and claimed.

This spray gun is intended to be operated from an air compressor unit and not from a storage tank of compressed air. In the usual non-bleeder type spray gun that is operated by a trigger, as soon as the operator releases the trigger so as to stop any further flow of compressed air through the gun, the air pressure will build up in the air hose and the air compressor will start to labor in its operation because it is forcing compressed air into a hose that is already filled with air.

An object of my invention is to provide a spray gun that does not have a trigger operated valve. Instead the air passage in the spray gun has a branch exhaust passage with an open outlet end that vents to the atmosphere. The open outlet end is placed near to the hand-grip portion of the spray gun so that the operator can grip this portion with one hand when using the spray gun and can take the index finger of the same hand to close the outlet end of the branch exhaust passage. His finger takes the place of the trigger operated valve of the usual spray gun and when it closes the outer end of the branch exhaust passage, the compressed air will flow through the gun to operate a novel spraying mechanism. When the operator wants to stop the spraying mechanism from operating while the air compressor is still working, he merely removes his finger from the outlet end of the branch exhaust passage. All of the compressed air from the air compressor will now be by-passed to the branch exhaust passage and be expelled to the atmosphere. The air compressor will not labor because there will be no building up of air back pressure. This may be termed a free bleeding of the air when the gun is not being used and is still connected to the air compressor. The spray gun will also be less expensive to manufacture because no trigger actuated valve is needed.

A further object of my invention is to provide a spray gun in which the novel spraying mechanism can be adjusted to spray a mist of liquid such as a stain or paint and also to spray droplets of the liquid. In many of the familiar types of spray guns there is an air delivery tube for moving a stream of air over the top of a liquid delivery tube whose lower end is immersed in the liquid to be sprayed. An entraining action of the liquid in the liquid conveying tube results and the liquid in the container will be drawn up in the liquid-conveying tube and will be atomized by the air stream.

In my novel spraying mechanism the horizontal tube is carefully positioned, far enough from the vertical tube, so that no entraining action of the liquid takes place. Instead, the mechanism delivers air into the top of the liquid container creating a mild air pressure of sufficient force to cause the liquid in the container to be forced into the vertical tube and to rise to the top of the tube. A horizontal stream of air is directed against the liquid at the point where it reaches the top of the vertical tube; the air is of sufficient force to atomize the liquid. As will be explained more fully hereinafter, the amount of air entering the container top can be controlled and consequently the rate of flow of liquid is also controllable. The quantity of air flowing horizontally over the top of the liquid conveying tube can also be controlled for either atomizing the liquid or breaking it up into droplets of varying sizes as desired.

2

Simplicity of structure is a main factor in this invention. The air compressor will operate cooler and with less strain because there is no build up of back pressure when actual spraying stops. There is no mechanism to clean and oil which is required when a trigger operated valve is used. By making simple adjustments the operator can produce a light or heavy spray or a spatter.

Other objects and advantages will appear as the specification continues. The novel features of the invention will be set forth in the appended claims.

Drawing

For a better understanding of my invention, reference should be made to the accompanying drawing, forming part of this specification, in which:

FIG. 1 is a side elevation of the spray gun with parts being shown in section.

FIGURE 2 is a top plan view of FIGURE 1.

FIGURE 3 is a side elevation of a portion of the spray gun and the liquid holding container.

FIGURE 4 is a transverse section taken along the line 4—4 of FIGURE 1.

While I have shown only the preferred form of my invention, it should be understood that various changes, or modifications, may be made within the scope of the annexed claims without departing from the spirit thereof.

Detailed description

30 In carrying out my invention, I provide a spray gun that has a body with a handle grip portion A and a channel-shaped member B. The handle may be made of wood or plastic while the channel-shaped member B is made of metal. It is possible to have the handle grip portion and the channel-shaped member cast as a single piece from a plastic or metal so I do not wish to be confined to the particular design and arrangement of these two parts.

40 The handle grip portion A has a top edge 10 and the sides of the member A that are disposed adjacent to the top 10 are provided with grooves 11 for receiving the side flanges 12 of the channel-shaped member B. Screws 13 and 14 or other suitable fastening means, see FIGURE 1, may be used for securing the channel-shaped member to the top of the handle grip portion A.

45 In FIGURE 2, I show the top of the channel-shaped member B and it will be noted that it has a disc-shaped end B'. This disc-shaped end has a container cap C secured thereto by rivets 15, see FIGURE 1. The cap C has an annular flange 16 that is threaded for receiving the threaded neck 17 of a fluid container indicated generally at D. The fluid container may be of any size desired.

50 The handle grip portion A has an air passage 18 that is in communication with an air hose E. The air hose in turn is connected to an air compressor, not shown. My spray gun is not designed to be used with a compressed air tank or reservoir. The air passage 18 has a branch passage 18a communicating therewith and this 55 leads to an air exhaust tube F that projects from the edge 19 of the handle grip portion A. FIGURE 4 shows the air exhaust tube F provided with an exhaust opening 20 in its side and this exhaust opening can be partly or completely closed by a sleeve valve G that is rotatably mounted on the air exhaust tube F. The sleeve valve has an exhaust opening 21 that may be brought into registration with the opening 20 of the air exhaust tube F as clearly shown in FIGURE 4. The handle grip portion A has a marker indicated by dotted lines 22 and this marker is placed adjacent to the periphery 23 of the sleeve valve G. In addition the periphery or outer 60 cylindrical surface of the sleeve valve G is calibrated 65 to indicate the amount of air being exhausted. The handle grip portion A has a top edge 24 that is provided with a 70 recess 25 for receiving the top edge 10 of the channel-shaped member B.

with a number of parallel markings indicated by the dotted lines 24 in FIGURE 1.

The operator can rotate the sleeve valve G on the air exhaust tube F into a desired position for entirely closing the exhaust opening 20 or for partially opening it or for entirely opening it as shown in FIGURE 4 when the opening 21 in the sleeve valve is brought into registration with the opening 20. In addition the air exhaust tube F has an end 25 that projects beyond the outer end 26 of the sleeve valve G and this end opens to the atmosphere. The open end 25 of the air exhaust tube F may be closed by the finger of the operator in a manner hereinafter described.

An air pipe H has its lower end communicating with the air passage 18 and has its upper end closed as at 26'. The air pipe H projects through an opening 27 in the channel-shaped member G. An air tube J communicates with the air pipe H and parallels the top of the channel-shaped member B. The air tube J extends through a bracket K that in turn is carried by the channel-shaped member B. The outer end of the air tube J is in the shape of an air nozzle 28 and this air nozzle is positioned close to a fluid outlet tube L. The tube L extends through aligned openings in the disc-shaped end B' and the cap C so as to be supported thereby. The tube L extends into the liquid container D when the latter is secured to the cap C. A flexible tube L' shown by the dotted lines in FIGURE 1, is connected to the lower end of the fluid conveying tube L and may be long enough to accommodate liquid containers, not shown, that are considerably larger than the liquid container D illustrated in FIGURE 1. The bottom of the flexible tube L' has a nylon screen L2 attached to prevent any impurities from clogging the tube L.

I provide novel means for forcing air into the liquid container D so that the air pressure built up within the container will force liquid out through the fluid outlet tube L. The purpose of the nozzle 28 for the air tube J is not for creating an entraining action which will draw fluid from the tube L but this nozzle will only project an air stream against the fluid that is forced out at the top of the fluid outlet pipe L. In the process of assembly, the end of the nozzle 28 is positioned to an exact spot where the entraining action is eliminated. Such a spot is slightly to the rear of the tube L and just a trifle higher than the position where the entraining action would be promoted. Novel means will presently be described that controls the amount of air pressure created in the top of the liquid container D and this air pressure in turn will control the amount of fluid discharged at the top of the tube L. In this way the operator can control the quantity of fluid sprayed against a surface, not shown.

A second air tube M communicates with the air pipe H and is supported by the bracket K. The air tube M parallels the first air tube J for an appreciable distance and then the air tube is inclined downwardly at an angle as clearly shown at M' in FIGURE 1. The outer end of the second air tube M is provided with a nozzle 29 and FIGURE 3 illustrates this nozzle as pointing directly at an air inlet tube N that feeds air into the top of the container D. The upper end 30 of the air tube N is cut at an angle of substantially 45° and when the air inlet end 30 for the tube N faces the nozzle 29 as clearly shown in FIGURE 3, substantially all of the air issuing from the nozzle 29 will be received in the chamfered end 30 of the tube N and will be directed into the top interior of the container D. It is this air pressure in the top of the container that will force fluid P out through the flexible tube L' and the fluid outlet tube L and will deliver this fluid at the top end 31 of the fluid outlet tube L.

I provide novel means for varying the quantity of air that enters the air inlet tube N. Both FIGURES 2 and 3

show the air inlet tube N rotatably mounted in the container cap C and the disc-shaped end B'. The tube N is provided with a handle Q and this handle is disposed just above the top of the disc-shaped end B'. The handle Q is provided with a pointer 32, see FIGURE 2, and this pointer travels over a series of markings numbered 1 to 6 inclusive and indicated at R. The markings may be depressions or projections in the disc-shaped end B' or they may be of a contrasting color to the main color of the disc-shaped end. The markings 1 through 6 are spaced equal distances apart and they form an arcuate row whose center is the rotating axis of the tube N.

When the pointer 32 for the handle or arm Q points toward the marking number "1," the chamfered entrance end 30 of the air inlet tube N will be facing directly toward the nozzle 29 and will receive substantially all of the air issuing from the nozzle. As the handle Q is rotated in a clockwise direction in FIGURE 2, it will rotate the chamfered end 30 gradually out of registration with the nozzle 29. As this rotation occurs, less of the air issuing from the nozzle 29 will be received by the inlet end 30 and therefore less air will be directed into the top of the liquid container D by means of the air inlet pipe N. The purpose of this will be explained more fully when describing the operation of the device.

When the pointer 32 of the arm Q registers with a marking 7 which is just to the right of the marking 6 in FIGURE 2, the plane of the inclined inlet end 30 for the tube N will be disposed in such a position that substantially no air will enter the opening 30. Therefore there will be insufficient air pressure in the top of the liquid container D to force liquid P out through the fluid outlet tube L. The operator can in this manner control the amount of fluid issuing from the top 31 of the tube. The lesser amount of fluid that is dispensed from the tube L will result in a less quantity of fluid being sprayed against a surface, not shown, by the air issuing from the nozzle 28 of the air tube J.

The sleeve valve G can be adjusted so as to entirely close the opening 20 in the air exhaust tube F and therefore when the operator closes the outlet end 25 of the tube F with his finger, all of the air entering the passage 18 from the air compressor and the flexible hose E, will flow into the tubes J and M with the result that the air from the tube M will be used in forcing air into the top of the liquid container D and thereby forcing liquid out through the opening 31 of the tube L and the air issuing from the nozzle 28 of the tube J will be used for spraying the liquid issuing from the outlet end 31. This amount of air to both tubes J and M can be reduced by rotating the sleeve valve G to partially uncover the opening 20 or to entirely uncover the opening 20 by bringing the sleeve opening 21 into registration therewith. The operator keeps his index finger closing the open end 25 of the air exhaust tube F during all of this adjustment of parts and therefore more liquid will be delivered from the pipe L when the opening 20 is closed by the sleeve valve G and more air will be forced from the nozzle 28 of the tube J to change the liquid into a spray and cause it to be directed against a surface, not shown. The amount of liquid dispensed through the opening 31 will be reduced as the opening 21 in the sleeve valve G is brought more and more into registration with the opening 20 in the exhaust tube F. Also less air will be delivered through the nozzle 28 of the air tube J for changing the liquid issuing from the opening 31 of the tube L into a spray.

Operation

The air hose E for the spray gun connects with an air compressor, not shown, and when the operator wishes to cut off the spraying of fluid against the surface of a short time, he merely frees his index finger, not shown, to uncover the open end 25 of the air exhaust tube F. All of the air flowing through the air hose E and into the air

passage 18 will flow out through the open end 25 of the air exhaust tube F into the atmosphere and there will be no back air pressure on the air compressor. Therefore the air compressor will not labor unnecessarily while it is still delivering air to the spray gun if the operator is not momentarily spraying liquid from the container D. This is a novel construction and no trigger or valve mechanism is needed. All that is necessary to make the spray gun operable is for the operator to use his forefinger to close the open end 25 of the air exhaust tube F.

I have already explained how the amount of liquid delivered by the tube L to the open end 31 of the tube can be altered by merely changing the quantity of air entering the top of the container through the air inlet pipe M. This amount of air is changed by adjusting the sleeve valve G to permit a desired quantity of air to escape through the openings 20 and 21 of the exhaust air tube F and the sleeve valve G respectively. Also the amount of air entering the top of the container can be 15 additionally controlled by swinging the arm Q for rotating the tube N with respect to the air nozzle 29 of the air tube M. When the pointer 32 is aligned with the marking "7" on the top of the disc-shaped end B', practically no air will be received by the tube N from the nozzle and no liquid will be delivered to the open end 31 of the tube L. When the pointer 32 is aligned with the marking numbered "1," substantially all of the air from the nozzle 29 will enter the tube N and find its way into the top of the container D. The greatest amount of liquid 20 will therefore be delivered from the opening 31 at the top of the tube L.

It is possible for the operator to spray a minimum amount of liquid against the surface and to thoroughly atomize this liquid. It is further possible for the operator to deliver greater quantities of liquid and to cause it to be sprayed as droplets onto the surface rather than as a mist. For example, when the air issuing from the nozzle 28 is at its maximum and the liquid issuing from the opening 21 at the tube L is at its minimum, the spray gun will deliver a fine mist of liquid against the surface. To obtain maximum amount of air for the nozzle 28, the open end 25 of the air exhaust F is closed by the operator's index finger and the sleeve valve G is closed. At the same time in order to obtain a minimum amount 40 of liquid to issue from the opening 31 in the tube L, the handle Q is swung for moving the pointer 32 so as to register with the marking "6" on the disc-shaped end B1. The maximum amount of air and a larger quantity of liquid can be realized when the handle Q swings the 45 pointer 32 to the number "5" position in the row of markings R. The mist issuing from the opening 31 of the tube L can be made heavier by rotating the sleeve valve G.

As the pointer 32 is swung over the markings R, in a counter-clockwise direction when looking at FIGURE 2, more air will enter the pipe N and a greater air pressure will be built up in the top of the liquid container D and more liquid will be forced out from the opening 31 of the tube L. Thus various settings of the pointer 32 will cause the spray gun to produce a mist or fogging up to a heavy spatter of liquid. The air from the nozzle 28 can also be varied. It might be implied from this that the air feed control for the nozzle 28 and the liquid feed control for the outlet 31 of the tube L are independent of each other. Actually a change in the setting of the sleeve valve G will alter the air flow in both of the tubes J and M. Therefore from a more technical standpoint, the adjustment of the liquid flow at the top of the spray gun by means of the handle Q is a refinement in the proportion of the mixture of air with the amount of liquid delivered. This control by the handle Q, of course, has no influence on the amount of air issuing from the nozzle 28 for the purpose of atomization of the liquid.

I claim:

1. A spray gun comprising:
  - (a) a body having a portion adapted to be gripped by the hand;
  - (b) a container cap carried by said body;
  - (c) a liquid container removably secured to said cap;
  - (d) a fluid discharge tube extending through said cap and being receivable in said container when the latter is secured to said cap;
  - (e) said body having an air passage therein for receiving air under pressure;
  - (f) an air nozzle communicating with said air passage and positioned adjacent to the outlet end of said fluid discharge tube for spraying any liquid discharged from said tube;
  - (g) adjustable air conveying means communicating with said air passage and with the top interior of said liquid container for delivering air under pressure into the container top for forcing liquid from the container and out through said discharge tube, said means being adjustable for varying the quantity of air entering the container top and thus varying the quantity of liquid discharged from said tube; and
  - (h) an air exhaust branch communicating with said air passage and having an outlet opening into the atmosphere so that when said exhaust branch is open, all of the air flowing through said air passage will escape to the atmosphere and no liquid will be discharged from said tube, said outlet opening being closed by the operator's finger for preventing any escape of air to the atmosphere;
  - (i) whereby liquid will be sprayed that is discharged from said tube.

2. The combination as set forth in claim 1: and in which

- (a) an adjustable sleeve valve is associated with said air exhaust branch and being openable to a desired extent for bleeding off a desired quantity of air to the atmosphere for reducing the amount of air delivered to said air nozzle and said air conveying means for altering the quantity of liquid discharged from said tube and thereby altering the amount of liquid spray delivered by the gun.

3. The combination as set forth in claim 1: and in which

- (a) said sleeve valve is calibrated for indicating the degree of angular rotation of said sleeve valve and the size of the opening to the atmosphere, the sleeve valve calibrations being associated with a marking on said body so as to move past said marking as said sleeve valve is rotated.

4. The combination as set forth in claim 1: and in which said adjustable air conveying means includes:

- (a) a second air nozzle communicating with said air passage;
- (b) an air inlet pipe for said container and being rotatably carried by said cap, the inlet end of said pipe being cut at an angle with respect to the axis of said pipe; and
- (c) a handle for rotating said pipe about its axis and being swingable from a position where the inclined inlet end faces said second air nozzle for substantially conveying all of the air issuing from said second nozzle into said pipe and into the top of said container for forcing liquid from said discharge tube, into a position where the inclined inlet end faces away from said second air nozzle and no air issuing from said second air nozzle will enter said pipe and no liquid will be forced from said discharge tube.

5. The combination as set forth in claim 4: and in which

- (a) said handle is provided with a pointer and said body is provided with an arcuate row of spaced apart

- markings over which said pointer travels when said handle rotates said air pipe about its axis;
- (b) whereby said air pipe can be angularly adjusted at different times to position the inclined end of said air pipe to face toward said second air nozzle or at a desired angle with respect thereto up to a point where said inclined end faces away from said second air nozzle.
